(57) **CLAIM**

I claim the ornamental design for a mouse, as shown and described.

DESCRIPTION

FIG. 1 is a perspective view of a mouse of our new design. FIG. 2 is a front view of the mouse shown in FIG. 1.

FIG. 3 is a rear view of the mouse shown in FIG. 1.

FIG. 4 is a right side view of the mouse shown in FIG. 1.

FIG. 5 is a left side view of the mouse shown in FIG. 1.

FIG. 6 is a top view of the mouse shown in FIG. 1; and,

FIG. 7 is a bottom view of the mouse shown in FIG. 1.

The mouse shown in FIGS. 1-7 illustrates our novel design suitable for use with a right hand. Our novel design also includes a second embodiment for use with the left hand, which is mirror symmetrical to FIGS. 1-7 and therefore not separately illustrated.

The broken lines shown in the figures represent portions of the mouse that form no part of the claimed design.

The thin solid lines shown in the figures represent contours only and do not illustrate an ornamentation or decoration on the surface of the mouse.

While the accompanying drawings include broken lines that form no part of the claimed design, the broken lines provide written description of prospective embodiments that are claimed when one or more of the broken lines are amended to solid lines. Similarly, while the solid lines in the drawings form part of the claimed design, the solid lines provide written description of prospective embodiments that are not claimed when one or more of the solid lines are amended to broken lines.
